Primary Examiner — Jonathan J Han*Assistant Examiner* — Caitlin Mackenzie Williams(74) Attorney, Agent, or Firm — Banner & Witcoff, Ltd.CLAIM

The ornamental design for a shoe as shown and described.

DESCRIPTION

FIG. 1 is a rear perspective view of a shoe showing my new design;
FIG. 2 is a side view thereof;

FIG. 3 is a front perspective view thereof;

FIG. 4 is an opposite side front perspective view thereof;

FIG. 5 is an opposite side view thereof; and,

FIG. 6 is an opposite side rear perspective view thereof.

The twelve broken line circles adjacent the tongue represent eyelets that form no part of the claimed design. The ten small broken line circles on the toe box represent holes that form no part of the claimed design. The broken lines immediately adjacent to the shaded area define the bounds of the claimed design and form no part thereof. The broken lines depicting the remainder of the shoe form no part of the claimed design.
